UNITED STATES PATENT OFFICE

JULIAN BUCHER, OF KANSAS CITY, MISSOURI.

PRINTING-PRESS.

1,079,161.

Specification of Letters Patent. Patented Nov. 18, 1913.

Application filed April 25, 1912. Serial No. 693,206.

To all whom it may concern:

Be it known that I, JULIAN BUCHER, a citizen of the United States, residing at Kansas City, in the county of Jackson and 5 State of Missouri, have invented certain new and useful Improvements in Printing-Presses, of which the following is a specification.

My invention relates to improvements in 10 printing presses, and the principal feature of the invention resides in means for keeping the ink plate of the press at uniform temperature in cold weather, so that said plate in turn will keep the ink thereon at 15 the proper consistency to obtain the best results in printing.

In cold weather more or less trouble is 20 experienced by printers in getting a uniform impression by reason of the fact that the ink when subjected to low temperature becomes thick, making it impossible to obtain an equal distribution thereof over the form, which results in getting too much ink in some places and not enough in other 25 places on said form.

By employing my invention the ink is at 30 all times retained at proper consistency to obtain equal distribution over the form, and in order that said invention may be fully understood, reference will now be made to the accompanying drawing, in which:

Figure 1 is a broken side elevation partly 35 in section of a press provided with my improvement, and Fig. 2 is a diagram showing the circuit of the electric heater employed in carrying out my invention.

Referring in detail to said drawing, 1 designates the bed of a job press provided 40 with a rotary plate 2 having a ratchet-wheel 3 at its underside. Plate 2 and its ratchet wheel 3 are rotated step by step by a gravity pawl 4, actuated by an oscillatory lever 5, which in turn is actuated in the ordinary manner by a movable portion (not shown) 45 of the press.

6 designates the ink font for supplying the inking rollers (not shown) with ink, which inking rollers pass over the form (not shown) and the plate 2, which latter in turning distributes the ink uniformly upon said 50 inking rollers in the customary manner.

Mounted upon bed 1 and just beneath the lower end of plate 2 is an electric heater 7, provided with the customary resistance coils 8 and 9, communicating at one end with a 55 source of electrical energy 10 through a wire 11 and communicating at their opposite ends with wires 12 and 13 leading to contact points 14 and 15, respectively, adapted to be engaged one at a time, by switch 16 communicating with a rheostat 17 through a wire 18, said rheostat communicating with a source of electrical energy 10 through the wire 19. By proper manipulation of the rheostat 17 and the switch 16, any degree of 65 heat is obtained which in turn warms the plate 2 and keeps the ink thereon at proper consistency for equal distribution over the distributing rollers and the form. 60

Having thus described my invention what 70 I claim and desire to secure by Letters Patent, is:—

Means for heating the rotary ink plate 75 of a printing press consisting of an electric heater including two resistance coils located on the press bed at a point beneath the ink plate and at the lower front end of said plate, a source of electrical energy, a contact for each coil in electrical connection therewith, a rheostat in electrical connection 80 with the source of energy, a switch movable from one contact to the other, and an electrical connection between the switch and rheostat.

In testimony whereof I affix my signature 85 in the presence of two witnesses.

JULIAN BUCHER.

Witnesses:

SAM J. LUGKETT,
W. J. PHIFER.
